LORENZO H. GILSON, OF BROCKTON, MASSACHUSETTS.

SHOE-BOTTOM CONSTRUCTION.

Application filed February 14, 1923. Serial No. 618,944.

In the manufacture of welt shoes the innersole is formed with a projecting sewing rib about the margin of its forepart and shank to which is stitched the upper and welt, this rib often being formed by channeling the sole along a line somewhat within the margin and toward the margin and then lifting the inwardly inclined flap formed by this operation. This construction leaves an open marginal groove of triangular cross section on the lower face of the insole which is bridged by the out sole. Wear of the shoe causes the innersole to become deformed so that its lower face is supported throughout substantially its whole extent on the out sole. This forms a gutter in the sock face of the innersole within the shoe which follows the weakened line of the channel and causes the shoe to become uncomfortable. Attempts have been made to correct this condition by filling the open channel on the lower face of the innersole with ground cork, leather scraps or plastic filler. This is a troublesome operation and has not been successful in correcting the difficulty because such fillers will creep, shift and pack under the pressure of the foot.

According to the present invention a strip of leather, rubber, or any other suitable material is formed or cut in cross section to the contour of the channel and is made fast therein. This is entirely effective to correct the trouble above mentioned. This filler strip may be formed in long lengths similar to the "continuous" or "endless" welt, it being perfectly feasible to form or wind it on reels containing as much as 1300 yards each. This avoids the necessity of cutting and fitting pieces within the channel of the shoe, and permits the utilization of the material without substantial waste, and with the minimum of time and trouble for the shoemaker.

As the finished strip, if formed from a single layer of leather, would require comparatively heavy and expensive stock, this invention also contemplates forming the filler strip of layers or laminations secured together, a practical method of forming the built up strip having been devised.

For a more complete understanding of this invention, together with further objects, reference may be had to the accompanying drawings in which—

Figures 1 and 2 show side and edge views, respectively, of a strip of leather to be used in forming a laminated filler strip.

Figures 3 and 4 are edge and side views, respectively, showing the manner in which the laminations are cemented together to form a continuous strip.

Figures 5 and 6 show the compound strip cut lengthwise to form continuous strips of the required width.

Figures 7 and 8 are perspective views showing the manner of cutting each strip diagonally to form a pair of finished channel filler strips.

Figure 9 is a perspective of a piece of the finished filler strip.

Figure 10 is a perspective of a package comprising a reel with the continuous filler strip wound thereon.

Figure 11 is a lateral section through the sole portion of a shoe substantially on line 11—11 of Figure 12 showing the channel filler strip in position.

Figure 12 is an inverted plan of a shoe before the sole has been applied and showing the filler strip in position.

Referring first to Figures 11 and 12, at 1 is indicated an innersole having a marginal inseam-receiving rib 2 formed thereon, this rib being formed by channeling the lower face of the innersole as shown at 3 and lifting the flap formed by the channeling operation. This lifting of the flap leaves an open triangular channel which is indicated at 4. The welt is indicated at 5 and is attached to the rib 2, the upper 6 and lining 7 interposed therebetween, by the inseam 8. The out sole 9 is attached to the welt in the usual manner by stitching 10. When no filler is employed for the channel 4 it is found that in use the innersole sags into the space formed by the channel, its upper or sock face becoming indented or guttered, and its lower face being supported by the out sole throughout substantially its entire extent. This gutter or groove which develops on the upper face of the innersole causes the shoe to be uncomfortable to the wearer.

This invention, therefore, provides means for filling the channel in the lower face of the innersole so that it will not become deformed in this manner. For this purpose a strip of material, such as leather, rubber,

2
or of any other suitable description, is formed or cut into a length having a uniform cross-section homologous to that of the open channel 4. This filler strip may then be laid within the channel as shown at 12 so as to take the place of the uplifted flap which is partly removed by the inseam trimming operation. This filler strip is formed in long lengths in the manner of the so-called "continuous" or "endless" welt. It is therefore unnecessary to piece the strip within the channel of the shoe, the strip being placed in position in the channel and cut off as required, being preferably cemented in position. This not only eliminates the labor of piecing the material when the shoe is being made, but also prevents the waste resulting from trimmings from the individual shoes. The filler strip may, if desired, be wound up on holders consisting of reels such as shown at 15 in Figure 10, and may be of considerable length, it being usual in practice of this invention to wind 1300 yards on a single reel. It may, of course, be packaged in any other suitable or convenient way.

In case it is desired to form the filler strip from laminations secured together this may be accomplished in the manner disclosed in Figures 1 to 8. Referring to Figures 1 and 2, 20 indicates a strip of material thinner than the desired filler strip and considerably wider. These strips 20 are scarfed at their ends and may be cemented in superposed face to face relation, the scarfed portions breaking joints in adjacent laminations as shown in Figures 3 and 4. This forms a continuous compound strip of the thickness required but of a width a multiple of the width of the desired filler strip. The purpose of forming the strip in this manner is to save labor in the handling of material, each piece containing stock for several finished strips, and to insure a proper bond between the laminations, this being more effectually accomplished when the strips are wider than the desired finished filler. The wide strip is then split up into strips of the finished width, Figure 5 showing the strips split once and Figure 6 showing each of these strips split again to form strips 22 rectangular in cross section and of the width of the desired channel filler. Each of these strips is then split along a cross sectional diagonal, shown at 23 in Figures 7 and 8, to form a pair of strips 25 of triangular cross section of the required dimensions, a portion of the finished strip being indicated in Figure 9. By this means a laminated strip of triangular section is produced, the laminations lying parallel to one face of the strip. While two laminations are shown, more might be used, if desired, to build up the material to the required thickness. The method of building up a

strip before it is cut insures that the laminations are properly bonded in the final product.

It will be understood from the foregoing that the shoe, in which the channel filler is used, will have a bottom which is substantially "all leather" with a smooth joint between the filler and insole face, leaving very little, or no space, between the insole and outsole for the introduction of the usual soft, ground-cork bottom filler. As a result the portion of the insole weakened by channeling and then trimming the channel flap is adequately supported and its sock surface remains smooth and comfortable because a guttering of this surface along the line of the channel is prevented because of the presence of the leather channel filler which will not creep or become misplaced.

While the features of the invention have been shown and described in their preferred embodiment, it will be understood that the invention may be embodied otherwise than as shown in the drawings and described in the specification and yet be within the scope 85 of the following claims.

Having thus described an embodiment of this invention what is claimed as new is:

1. In combination with a shoe having a channeled innersole presenting a triangular open channel, a strip of triangular cross section and uniform from end to end filling said channel.

2. In combination with a shoe having a channeled innersole, a leather strip continuous and uniform from end to end, and of a cross-section homologous to that of the channel, filling the same.

3. A welt shoe having a bottom comprising a channeled innersole having a triangular open channel, a welt and an outsole, and a leather filler strip of triangular cross-section laid in said open channel between said innersole and said outsole to support the substance of the innersole that forms the bottom of said channel and prevent a wear-gutter forming in the sock surface of the innersole.

4. A welt shoe having a bottom comprising a leather innersole presenting a channel area within the sewing rib, a welt and an outsole, and a leather channel strip paralleling the welt, said strip having an outer edge face abutting the shoulder at the outer side of the channel area and an inner skived edge to form a substantially smooth joint with the face of the innersole at the inner side of the channel area, thereby filling the channel area and affording a substantially flat and homogeneous tread surface within the welt and opposite the inner face of the outsole.

In testimony whereof I have affixed my signature.

LORENZO H. GILSON.
